UNITED STATES PATENT OFFICE

RICHARD HOWLAND RANGER, OF NEWARK, NEW JERSEY, ASSIGNOR TO RADIO CORPORATION OF AMERICA, A CORPORATION OF DELAWARE

SYNCHRONIZATION OF FACSIMILE TELEGRAPH APPARATUS

Application filed August 19, 1925. Serial No. 51,191.

This invention relates to certain new and useful improvements in speed regulation of electric motors and more particularly to a method of an apparatus for obtaining an absolutely constant and invariable speed of 5 such a motor. While it will be understood that my invention is of general application and may be used in all situations in which extremely constant speed is required, it is particularly adapted to systems for the transmission and reception of facsimile messages, such as pictures, copies of documents and the like either by radio or by wire line.

In the past various methods have been suggested for obtaining constant speeds, but in 15 general these methods have failed to give the desired results, particularly when used in apparatus in which a very great constancy of speed is required, such as in facsimile telegraphy in which the transmitting and receiving apparatus is required to be synchronized.

Many methods have been suggested in 20 which synchronization has been attempted by regulation of one motor by another by means of impulses delivered by the first to the second. The fundamental idea of such methods is that the second motor is thus caused to follow the first motor in respect to all variations of speed.

I have found that in practice and more particularly in the transmission of facsimile messages by radio, as distinguished from such transmission by wire line, it is impracticable to attempt to regulate the speed of 25 one motor by the speed of another. Particularly, it is impracticable to attempt to adjust the speed of the motor at the receiver to the speed of the motor at the transmitter 30 by means of correcting impulses periodically sent by the transmitter.

The effect of atmospheric disturbances, commonly called static, strays, x's and the like is such that, no matter what type of 35 impulses are used so far as I know, these atmospheric disturbances always interfere with and upset the synchronization of transmitter and receiver according to any method requiring the transmission of synchronizing or 40 correcting signals.

It is an object of this invention to produce a system and apparatus for the transmission of facsimile messages which is not subject to disturbance by atmospheric disturbances, static, or other forms of interference.

It is a further object of this invention to produce a system and apparatus for the transmission of facsimile messages without requiring the transmission of synchronizing signals between transmitter and receiver.

It is a further object of this invention to produce a system for the transmission of facsimile messages in which the transmitting and receiving apparatus is synchronized or adjusted to the same speed independently.

It is a further object of this invention to produce a speed regulating system of sufficient accuracy and sensitivity to permit independent adjustment of transmitter and receiver to the same speeds without the transmission of synchronizing signals.

It is a still further object of my invention to provide a speed regulating system which shall be positive and effective and which will regulate speed to a greater constancy than systems hitherto known in the art.

Still other objects will be apparent from the specification.

Satisfactory synchronization without the transmission of synchronizing signals is in 45 reality a problem of speed regulation, since it is possible to obtain tuning forks, pendulums, clocks and the like, which can be regulated very closely to the same frequency or speed. If then the transmitter can be rigorously held to the speed determined by such a means, transmitter and receiver may be independently adjusted and held to the same predetermined speed.

Since I do not use any correction or control between transmitter and receiver in operation and since it is necessary in synchronizing according to my invention only that the tuning forks, pendulums, clocks or the like used for regulation have nearly the same 50 frequency period or speed, I have shown and described my invention with reference to a single motor which may be used to drive a transmitter or receiver as the case may be, but it will be understood that in the transmission 55

of pictures by apparatus embodying my invention, the same method will be used for synchronizing at each end.

I have found that by the use of a tuning fork, for example, so chosen as to make one complete beat in approximately the time that the motor normally makes one complete revolution, it is possible to arrange circuits which will regulate a motor to an approximately constant speed which may be satisfactory for certain purposes. In general, however, for the transmission of facsimiles a still greater constancy of speed is necessary and for this purpose I apply a correction proportional to the departure of the motor from the speed desired, but of relatively minor effect or what may be termed a vernier correction.

Briefly, it may be stated that according to this invention a rough speed adjustment or correction of the motor speed proportional to the departure from the desired speed is applied by the tuning fork at least once during every revolution of the motor which suffices to give an approximately constant speed and in addition to this, I apply a vernier correction at relatively long intervals, for example once every second, which, while of itself not sufficient to hold the motor to a constant speed, is sufficient when applied as a correction to the approximately constant speed maintained by the tuning fork.

The novel features which I believe to be characteristic of my invention are set forth with particularity in the appended claims. My invention itself however, both as to its organization and method of operation together with further objects and advantages thereof, will best be understood by reference to the following description taken in connection with the accompanying drawings, in which

Fig. 1 is a diagrammatic view of a circuit in accordance with my invention; and

Fig. 2 is a chart illustrating the action of the speed controlling means.

Referring more particularly to Fig. 1, 1 designates generally an electric motor, herein shown as of the shunt-wound type having an armature 2 and a field winding 3. For the purpose of controlling the speed of this motor, as will be more particularly set forth hereinafter, I provide a tuning fork herein shown as 4. It will be understood, however, that the use of a tuning fork is not an essential part of my invention but that any other suitable or equivalent apparatus may be substituted for the tuning fork, the only requirement being that the element 4 should be a mechanical or electrical vibrator or oscillator of relatively constant frequency and of the order of frequency of the motor speed expressed in revolutions per second.

For the purpose of driving the tuning fork 4 I have shown a coil 5 connected in the customary way to keep the fork in vibration,

as is well understood in the art. Specifically, the coil 5 is connected on the one hand through a suitable resistance shown as 7 to one side of the supply line indicated as — and on the other hand through contact 8 and the fork 4 to the other side of the line indicated as +.

It will be understood that after the fork is once set into operation, the vibration of the tine to and away from contact 8 will cause current impulses through the coil 5 which will cause the fork to continue to vibrate. In addition, I have shown a coil 6 connected across the source of supply in circuit with a variable resistance 14, the purpose of which is to give what may be termed a vernier adjustment of the fork frequency. It will of course be understood that any suitable means may be provided for varying the frequency of vibration of the fork 4, such for instance as sliding weights mounted upon the tines or any other equivalent arrangement.

From this it will be understood that the fork 4 may be set into vibration and maintained in vibration at a substantially constant frequency and that the frequency may be varied within limits to the extent desired. By the operation of suitable adjustments, the fork 4, as will hereinafter be pointed out, is arranged to control in what may be termed a coarse way the speed of the motor. This may be accomplished by the following arrangement, for example.

Driven by the shaft of the motor 2, and preferably but not necessarily mounted thereon, I provide a brush 20. Cooperating with this brush 20 I provide a commutator designated generally by 21 and having, for example, four segments 22, 23, 24 and 25. As shown, two of these are connected together; for example, 22 and 24 are so connected; likewise 23 and 25. From brush 20 a connection is made to contacts 12, 13, adapted to be closed by the vibration of the fork 4, and the fork 4 is itself connected to one side of the line, as previously pointed out.

In the armature circuit I provide a resistance, herein shown as 14', and in the field circuit I provide a suitable resistance 15. The commutator segments 23 and 25 are connected at an intermediate point between resistance 14' and the armature 2. In a similar way segments 22 and 24 are connected at an intermediate point between field 3 and resistance 15. I have also provided resistances 16 and 18 in series with condensers 17 and 19 respectively across the field and armature terminals for the purpose of smoothing out the current flowing therein, but these form no essential part of my invention.

Similarly, I have shown resistance 28 in series with condensers 26 and 27 respectively connected between brush 20 and adjacent segments of commutator 21. These likewise

form no essential part of my invention. I have also shown condensers 10 and 11 connected between contacts 8, 12 and 13 respectively and an additional resistance 46 for connecting the point between condensers 10 and 11 to the source of supply. It will be understood also that these form no essential part of my invention.

It will now be apparent that on the closure of switch S in the motor circuit the motor 1 will be set into operation. The tuning fork 4 may also be set into operation by tapping it and the fork will preferably, but not necessarily, be so adjusted that its frequency is substantially the same as the number of revolutions per second of the motor.

As the motor shaft revolves, brush 20 will sweep around the segments of commutator 21 and will alternately close a circuit from the terminal of the armature circuit connected to resistance 14' around the resistance 14' to contacts 12 and 13 of the fork and from the terminal of the field winding connected to resistance 15 around the resistance 15 to the same point. If now fork 4 is in contact with either of contacts 12 or 13, a circuit will be completed to the positive side of the supply line, short-circuiting alternately resistances 14' and 15.

It will readily be understood that the short-circuiting of resistance 14' in the armature circuit will cause the motor to tend to speed up and on the other hand, short-circuiting of resistance 15 in the field circuit will cause the motor to tend to slow down.

Referring to section A of Fig. 2, I have shown diagrammatically the action of the commutator 21 and brush 20 in cooperation with the fork 4. The closures of the various contacts are plotted against time. By referring to the first line, it will be seen that brush 20 closes successively a circuit through commutator segments 24, 23, 22 and 25. It will be apparent from what has already been said that the closure of the circuit through segments 24 and 22 prepares a circuit for slowing down the motor by short-circuiting the field resistance, and on the other hand the closure of the circuit through segments 23 and 25 prepares a circuit for speeding up the motor through the short-circuiting of armature resistance. These closures are designated F and S, meaning faster and slower.

Referring further to section A of Fig. 2, it will be seen that through the alternate closure of contacts 12 and 13 with the fork 4, a circuit is periodically completed from points 12 and 13 to the positive supply line. In case the motor and fork are operating at the same speed, that is to say, the motor making one complete revolution while the fork makes one complete beat, it will be apparent that there will be what may be termed a speeding up impulse given to the motor twice during a revolution and what may be

termed a slowing down impulse twice during a revolution. One of these speeding up impulses will occur while the brush 20 is passing over commutator 23 and while contact 13 is closed by fork 4. One of the slowing down impulses will occur immediately afterward while brush 20 is passing over a portion of commutator segment 22 and while contact 13 is still closed. If the motor is operating at the same speed as the fork and neither gaining nor losing, these speeding up and slowing down impulses will be exactly equal in length and owing to the inertia of the armature no change in speed will occur.

If on the other hand the motor is tending to slow down, the conditions will be as shown in section B of Fig. 2; that is to say, brush 20 will lag behind the position it should take and instead of the alternate speeding up and slowing down impulses being of equal length, the speeding up impulses will increase in length and the slowing down impulses will decrease in length. This will of course cause the motor to tend to speed up to a point where the pulses are equal in length.

In a similar way, it will be seen that if the motor tends to speed up, conditions are as shown in section C of Fig. 2, wherein brush 20 is in advance of the position which it should have and closes its circuit through the commutator segments too soon. The result of such action is to cause the time of the slowing down impulses to increase and the time of the speeding up impulses to diminish, thereby tending to slow the motor to the proper speed.

By the use of the arrangement just described, it is possible to obtain what may be called a rough adjustment of speed. The adjustment however, while it may be satisfactory for some purposes, does not give the extreme constancy of speed that I have found desirable for certain purposes and for the purpose of making it still more nearly constant, I have provided further means for obtaining a very fine adjustment of speed.

For this purpose I have made use of a standard or precision clock, such as diagrammatically illustrated at 29 as a pendulum having a contact 30. The clock per se forms no part of this invention and is therefore not described in detail, it being sufficient for the purposes of this invention to state that there is provided a contact 30 closed for example once every second by the clock 29.

The contact 30 is connected to one terminal of the source of supply as shown and the contact on the clock 29 is connected through suitable resistance 36 through coil 34 to the other side of the supply line. A circuit is also established through coil 35 and suitable resistance 37 through contacts 32 and 33 closed by a cam 31 driven by motor 2 and which will preferably be arranged to close contacts 32 and 33 at the same time and as often as con-

tact 30 is closed by clock 29. An obvious means to rotate the cam 31 so as to turn same one revolution during each swing of the clock pendulum 29, is to drive the cam through a reduction gearing driven from the motor shaft. The reduction gearing may be of any preferred ratio to give the desired speed rotation to the cam. Coils 34 and 35 are so arranged as to control a suitable armature 42 and attract it against contact 41 or against a suitable dummy contact.

Armature 42 is connected as shown to one side of the source of supply and is also connected through a suitable small motor having an armature 39, field coil 38 and a suitable resistance 43. Motor 39 is arranged to control the position of commutator 21 by means of any suitable driving mechanism, such for instance as worm 44; that is to say, operation 20 of the motor will cause a slow rotation of commutator 21.

Connected to one side of the armature 39 of this motor I provide a resistance 40 which in turn is connected to contact 41. When the 25 armature 42 is closed against contact 41, a circuit of suitable resistance will be established around the armature and current will be diverted from the armature. The constants are preferably chosen so that when 30 armature 42 is closed against contact 41, the motor will just not operate and when armature 42 is attracted against the dummy contact, the motor will operate and commutator 21 will be slowly rotated.

35 It is to be noted that coils 34 and 35 are so arranged that the effect of coil 35 predominates and is sufficient to attract armature 42 against contact 41, although coil 34 may in fact be energized. It will also be understood 40 that armature 42 will remain in either of the positions in which it happens to be until it is attracted to the other position by either coil 34 or 35. The operation of this apparatus will now be clear.

45 If the motor 1 is operating at precisely the desired speed, contact 32 will be closed against contact 33 by the action of cam 31 exactly as often as contact 30 is closed by the action of clock 29. If these closures take place 50 simultaneously, nothing further happens, armature 42 being attracted against contact 41 by the action of coil 35, thereby diverting current from armature 39 through resistance 40. If, as may be the case, these do not occur 55 simultaneously, then for a certain part of the time armature 42 will not be attracted against 41 and the small motor will operate, shifting commutator 21 in a direction to cause the motor to speed up or slow down for a short 60 time, until the closures are simultaneous.

For the purpose of indicating whether or not the motor is operating at the speed desired, I provide a small lamp 45 which may conveniently be mounted off center upon the 65 motor shaft. While the particular type of

lamp used forms no part of my invention, it is evident that one should be used which has practically no thermal inertia and for this purpose I have found a small neon lamp to be satisfactory.

70

The circuit through this lamp may be closed, for example, once a second by the closure of fork 4 on contact 9, thereby energizing auto-transformer 46 for a short time, once per beat of the fork. If the motor is running in synchronism with the fork and the lamp is observed, it will be seen as a point of light standing stationary upon the motor shaft. If the motor is running slow, the point of light will appear to be moving backwards, that is, against the direction of rotation and if fast, to be moving forward.

75

It will be understood that manually operable means may be provided for carrying on the speeding up and slowing down operations. 80 herein set forth, such as manually operable switches for varying armature or field resistance and for operating motor 39, and also manually adjustable or controllable means for shifting the position of contacts 32 and 33 with respect to cam 31. It will also be understood that this position may be shifted by a suitable motor and gearing.

85

While I have shown and described the preferred embodiments of my invention, it will 90 be understood that I do not wish to be limited to precisely the form shown and that modifications and changes may be made without departing from the spirit of my invention.

95

Having described my invention, what I 100 claim is:

1. A method of synchronizing apparatus used in the transmission and reception of messages by radio which is unaffected by static which consists in adjusting the driving apparatus of the transmitter and receiver independent of connecting channels therebetween to substantially constant speeds at relatively frequent intervals, and in applying secondary adjustments to the driving apparatus of the transmitter and receiver also independently of each other at relatively widely separated time intervals.

105

2. A method of synchronizing apparatus used in the transmission of facsimile messages by radio which is unaffected by static, which consists in controlling the speed of driving mechanism of receiver and transmitter independently of connecting channels therebetween by separate constant frequency vibrators for giving a coarse speed adjustment and a second set of constant frequency vibrators for giving a final speed adjustment.

110

3. A method of regulating the speed of a moving mass which comprises applying a correction responsive to deviation from desired speed at relatively frequent intervals and applying at relatively long intervals with respect to said first mentioned correc- 115

120

125

130

- tion a further correction responsive to deviations from desired speed.
4. A method of regulating the speed of a moving mass which comprises applying a correction responsive to deviation from desired speed and substantially coincident in time therewith and applying at relatively long intervals with respect to said first mentioned correction a further correction responsive to deviation from desired speed integrated over a relatively long period of time.
5. A method of regulating the speed of a moving mass which comprises applying a correction responsive to deviation from desired speed at relatively frequent intervals and applying a correction in response to deviations from desired speed too small to be corrected by said first correction and only at relatively long intervals.
6. A method of regulating the speed of a moving mass which comprises applying a correction responsive to deviation from desired speed at relatively frequent intervals to maintain an approximation to desired speed and applying a further correction in response to deviation integrated over a relatively long period of time to maintain exact desired speed.
7. A system for regulating the speed of a movable mass comprising, in combination, means responsive to instantaneous deviation of said mass from desired speed for applying a correction thereto, and means operable at relatively long time intervals for applying a correction responsive to deviations in desired speed integrated over said intervals.
8. A system for regulating the speed of a movable mass comprising, in combination, means responsive to instantaneous deviation of said mass from desired speed for applying a correction thereto and means operable at relatively long time intervals responsive to deviations in desired speed integrated over said intervals for initiating operation of said first named means.
9. A system for regulating the speed of a movable mass comprising, in combination, primary speed regulating means responsive to instantaneous deviation of said mass from desired speed for applying a correction thereto and secondary speed regulating means responsive to integrated deviations of speed for causing operation of said primary speed regulating means.
10. A system for regulating the speed of a movable mass comprising, in combination, a substantially constant frequency vibrating element, means for controlling the speed of said mass in accordance with the frequency of said vibrating element, a second constant frequency vibrating element of materially lower frequency than said first vibrating element and means for further controlling the speed of said mass in accordance with the speed of said second vibrating element.
11. A system for regulating the speed of a rotary body comprising in combination, a substantially constant frequency vibrating element adapted to make one vibration in substantially the time required by said body to make one revolution, a second constant frequency vibrating element adapted to make one vibration in the time required by said body to make a comparatively large number of revolutions and means controlled by both said vibrating elements for controlling the speed of said body.
12. A system for regulating the speed of a rotary body comprising in combination, a substantially constant frequency vibrating element adapted to make one vibration in substantially the time required by said body to make one revolution, means for controlling the speed of said body in accordance with the frequency of said vibrating element, a second constant frequency vibrating element of materially lower frequency than said first vibrating element and means controlled by said second vibrating element in response to deviations of said body from desired speed for causing operation of said controlling means.
13. A system for regulating the speed of a rotary body comprising in combination, a constantly vibrating current interrupter, a plurality of contacts arranged to be successively closed by said body in operation and means controlled conjointly by said interrupter and said contacts for periodically increasing and decreasing the speed of said body.
14. A system for regulating the speed of a rotary body comprising in combination, a constantly vibrating current interrupter of substantially constant periodicity, a plurality of contacts arranged to be successively closed by said body in operation and means cooperating with said current interrupter and said contacts for causing deviations of said body from desired speed to introduce a force for correcting said deviation.
15. A system for regulating the speed of a rotary body comprising, in combination, a substantially constant frequency current interrupter, a plurality of contacts arranged to be successively closed by said body in operation, and circuits connecting said interrupter and said contacts for periodically increasing and decreasing the speed of said body by substantially equal minute increments.
16. A system for regulating the speed of a rotary body comprising, in combination, a substantially constant frequency current interrupter, a plurality of contacts arranged to be successively closed by said body in operation, and circuits connecting said interrupter and said contacts for periodically increasing and decreasing the speed of said body by substantially equal minute increments, and such circuits being so arranged as to vary the ratio

between speed increasing and decreasing increments in response to deviations of said body from desired speed and in a direction to correct said deviation.

- 5 17. A system for regulating the speed of a rotary body comprising, in combination, a circuit operable to increase the speed of said body, a second circuit operable to decrease the speed of said body, a plurality of contacts 10 successively operable by said body for successively preparing said circuits at predetermined intervals and for predetermined times, and a constant frequency speed determining interrupter associated therewith and arranged to complete the operation of one or the other of said circuits and to vary the time interval of operation to maintain the speed of said body constant.

18. A system for regulating the speed of 20 a rotary body comprising, in combination, a circuit operable to increase the speed of said body, a second circuit operable to decrease the speed of said body, a plurality of contacts successively operable by said body for successively preparing said circuits at predetermined intervals and for predetermined times, a speed determining interrupter associated therewith and arranged to complete the operation of one or the other of said circuits and 25 to vary the time interval of operation to maintain the speed of said body constant, a second speed determining interrupter of materially lower speed than the first speed determining interrupter, a second set of contacts operable by said body, and means controlled conjointly by said second speed determining interrupter and said second set of contacts for varying the time intervals of operation of said circuits to correct for deviations in speed integrated over relatively long periods.

19. A system for regulating the speed of a rotary body comprising, in combination, a circuit operable to increase the speed of said body, a second circuit operable to decrease the speed of said body, a plurality of contacts successively operable by said body for successively preparing said circuits at predetermined intervals and for predetermined times, a speed determining interrupter associated therewith and arranged to complete the operation of one or the other of said circuits and to vary the time intervals of operation to maintain the speed of said body 45 constant, a second speed determining interrupter of materially lower speed than said first speed determining interrupter, a second set of contacts operable by said body, and means controlled by said second speed determining interrupter and said second set of contacts for varying the position of said first mentioned plurality of contacts with respect to said body.

20. A system for regulating the speed of 50 a rotary body comprising, in combination, a

circuit operable to increase the speed of said body, a second circuit operable to decrease the speed of said body, a plurality of contacts successively operable by said body for successively preparing said circuits at predetermined intervals and for predetermined times, a speed determining interrupter associated therewith and arranged to complete the operation of one or the other of said circuits and to vary the time intervals of operation to maintain the speed of said body constant, a second speed determining interrupter of materially lower speed than said first speed determining interrupter, a second set of contacts operable by said body, means for shifting the position of said plurality of contacts with reference to said body and means operable in response to non-coincident operation of said second speed determining interrupter and said second set of contacts for initiating operation of said shifting means.

21. In a speed regulating system for rotary bodies, a constant frequency current interrupter for controlling the speed of the body at relatively frequent intervals, a second constant frequency current interrupter for applying a secondary correction to the speed of said body at relatively long intervals with respect to said first named speed corrections, a visible indicator of speed rotating with the said body, and means controlled from the first of said named constant frequency vibrating devices for periodically illuminating said visible indicator whereby due to the rotation of said indicator with said body the relative speed thereof with respect to the rate of vibration of said first named constant period vibrating device may be stroboscopically observed.

22. In combination, a rotating body, a constant period vibrating device for controlling the speed of rotation of said body, a visible indicator attached to and rotating with said rotating body, and means controlled by said constant period vibrating device for illuminating said visible indicator a predetermined number of times during each rotation of said rotary body whereby the relative speed of said rotary body with respect to the controlling force thereon may be stroboscopically observed by observing the relative position at which illumination of said indicator occurs at successive rotations of said body.

23. A system for stroboscopically indicating the speed of rotating bodies and the like, which includes, a rotating body, a constant period vibrating device for controlling the speed of said body at each rotation thereof, a glow lamp rotating with said body, and means controlled by said constant frequency vibrating device for illuminating said glow lamp once during each rotation of said body whereby deviations in the speed of rotation of said body relative to the constant frequency vibrating control device may be ob- 130

served stroboscopically by determining relative changes in the position of the point of illumination of said glow lamp for successive rotations of said body.

- 5 24. In combination, a rotating body, a constant period vibratory means for controlling the speed of rotation of said body, a light source attached to and rotating with said rotating body and serving as a visible indicator of synchronism, and means for illuminating said light source a predetermined number of times during each rotation of said rotary body whereby the relative deviation in speed of said body with respect to the normal controlling speed may be stroboscopically observed.

RICHARD H. RANGER.

CERTIFICATE OF CORRECTION.

Patent No. 1,829,420.

October 27, 1931.

RICHARD HOWLAND RANGER.

It is hereby certified that error appears in the printed specification of the above numbered patent requiring correction as follows: Page 2, line 54, for "turning" read tuning; page 6, line 91, claim 21, for "frequently" read frequency; and that the said Letters Patent should be read with these corrections therein that the same may conform to the record of the case in the Patent Office.

Signed and sealed this 5th day of July, A. D. 1932.

M. J. Moore,
Acting Commissioner of Patents.
